UNITED STATES PATENT OFFICE.

JOHN E. SMITH, OF LAUREL, AND WILLIAM F. SULT, OF GILMAN, IOWA, ASSIGNORS
TO SUNLIGHT HAT CO., OF MARSHALLTOWN, IOWA.

VENTILATED HAT.

1,103,012.

Specification of Letters Patent.

Patented July 7, 1914.

Application filed April 11, 1912. Serial No. 689,971.

To all whom it may concern:

Be it known that we, JOHN E. SMITH and WILLIAM F. SULT, citizens of the United States, residing at Laurel and Gilman, respectively, in the county of Marshall and State of Iowa, have invented certain new and useful Improvements in Ventilated Hats, of which the following is a specification.

10 The present invention relates to improvements in ventilated hats, and particularly consists of a construction, the special features of which may be applied to any of the existing forms of soft and stiff hats, or even 15 straw hats.

The invention is designed as an improvement over the construction disclosed in our pending application filed November 18, 1911, Serial Number 661,108.

20 The main object of the invention is to provide a hat which, when in use, will afford a thorough ventilation of all portions of the sides and top of the wearer's head. The novel construction employed allows the 25 air to enter between the sweatband and crown, through a plurality of spaced openings formed throughout the lower edge of the hat at the region where the lower edge of the sweatband and the inner edge of the 30 brim of the hat engage the wearer's head, and to circulate between such openings and additional openings which are formed in the upper portion of the crown.

To this end, the invention consists in 35 spacing the sweatband throughout its circumference from the inner side of the lower portion of the crown adjacent thereto, the air passing through these spaces during its circulation between the openings in the 40 lower edge of the hat and those formed in the crown. The spacing is effected by the insertion of a strip between the sweatband and the crown, and which is folded in a peculiar manner in order to obtain the spacing 45 effect.

For a full understanding of the present invention, reference is to be had to the following description and to the accompanying drawings, in which—

50 Figure 1 is a side elevation of a hat having our novel improvements embodied therein, a portion being shown in section. Fig. 2 is an under plan view of the hat. Fig. 3 is a central section. Fig. 4 is a detail under 55 plan view showing a portion of the struc-

ture in section. Fig. 5 is a sectional view taken through the sweatband and spacing means hereinafter described.

Throughout the following detail description and on the several figures of the drawings, similar parts are referred to by like reference characters.

In the drawings, the improvements constituting the present invention are shown as applied to a soft hat of conventional design, having a crown 1 and brim 2. A sweatband 3, preferably constructed of leather, extends, as is ordinarily the case, throughout the inner circumference of the hat, and has its lower edge 4 turned upwardly and preferably stitched throughout the length of such edge to the lower portion of the crown 1, this arrangement being shown particularly in Fig. 5.

At spaced intervals throughout its circumference, the sweatband is formed at its lower edge with a plurality of openings 5 for the admission or exit of the air which will circulate through the hat by virtue of the particular construction employed. These 60 openings coöperate in a novel manner with the spacing means included between the sweatband and the crown of the hat. A short distance above the openings 5, another row of openings 6 is formed, the same extending throughout the inner circumference of the sweatband, the openings of this second row being placed in staggered relation to the openings first described.

In the practice of the invention, we may, 75 however, dispense with the row of openings 6, if desired, as in some cases sufficient ventilation may be afforded by simply employing the row of openings 5.

We will now describe the particular 80 means employed by which the spacing of the sweatband from the lower portion of the crown of the hat adjacent thereto, is obtained.

A strip 7 which, in practice, will possess a 85 width slightly less than the width of the hat engaging portion of the sweatband, is folded in a manner best illustrated in Fig. 4. The strip 7 may consist of leather, light metal, a stiff fabric, or any other material 90 suitable for the purpose, and before being placed between the sweatband and the crown of the hat, the material is folded upon itself at spaced intervals, which, when the strip is 95 inserted in place, will extend throughout the 100

105 plan view showing a portion of the structure in section. Fig. 5 is a sectional view taken through the sweatband and spacing means hereinafter described.

circumference of the hat. These folds form what are substantially a series of pairs of tubular chambers 8, and pairs of oppositely disposed spaces 9, separated by a wall which 5 forms part of the body of the strip 7. The openings 5 will be so disposed with reference to the folded strip 7 as to communicate with the tubular passages 8 and the ends of the spaces 9, so that air entering through the 10 openings will pass upwardly through the said tubular passages and spaces, into the interior portions of the hat above the sweatband, and out through the openings in the top of the crown hereinafter referred to or, 15 of course, the movement of the air may be reversed.

It will be seen that the strip folded in the manner described affords at a plurality of points throughout its circumference three 20 thicknesses of material forming the body of the strip, by which means the sweatband is effectively spaced from the crown, and will be so maintained with reference thereto at all times that the hat is worn. The openings 25 6 referred to communicate with the inner spaces 9 so as to admit air thereto and thus a more complete ventilating effect may be had. The strip 7 may be maintained in its proper position either by stitching it to 30 the sweatband at the places where it contacts with the same, or by employing an adhesive at such places.

While the structure of the parts referred to in the foregoing constitute the essential 35 novel features of the present invention, we, however, provide a series of openings 10 formed in the upper portion of the crown of the hat in the manner particularly shown in Figs. 1 and 2. These openings, in themselves, do not comprise a feature of novelty but, in the present invention, they coöperate with the openings 5 and 6 in such a manner as to obtain a complete and thorough ventilation of all portions of the wearer's head.

40 The improvements herein described will afford an advantageous effect when the invention is used, in connection with any of the existing forms of hats, but the effect is peculiarly advantageous when the invention is applied to a soft hat. In this case, the air circulating between the openings 10 and the openings 5 and 6 will tend to always maintain the material forming the crown out of close contact with the wearer's head, 45 and thus exerts a beneficial cooling effect.

A row of openings 11 is formed in the strip 7 substantially opposite to the openings 6 formed in the sweatband, as seen in Fig. 4. They would be of advantage, however, in case portions of the strip 7 between

the tubular chambers 8 should be forced closely against the sweatband and would then permit the air to pass to the opposite space 9, the latter being under such conditions larger than ordinarily.

65

It is apparent particularly from Fig. 4 of the drawing that the fluted filler strip 7 is formed into successive compound convolutions providing spaced multiple thicknesses forming the passage-ways 8 at each compound convolution, with the spaces 9, 9 along the length of the strip between the respective points of the folds, with the apertures 5, 6 and 11 disposed to admit of and insure free and continuous circulation.

70

75

Having thus described the invention, what is claimed as new is:

1. In a ventilated hat, the combination, with a crown, of a sweat band arranged therein and a fluted strip disposed between the sweat band and the crown and folded into successive compound convolutions, the folds of the convolutions being spaced for forming a double passage-way at the points of the fold and leaving passage-ways at each side of the strip between the points of the respective folds, the strip and band being formed with apertures permitting free circulation through and about all passage-ways formed by the material of the strip and between the strip and adjacent parts.

80

2. A ventilated hat, comprising a crown and a sweatband turned upwardly at its lower edge, said upwardly turned portion being attached to said crown, said sweatband being provided with a plurality of openings at the edge where it is turned, and having an additional row of openings located above said edge, and a strip disposed between the sweatband and the adjacent portion of the crown, said strip being folded upon itself at intervals to afford several spaced thicknesses of material at such folded places for affording a series of tubular passages which communicate with said first 95 named openings, and also affording a series of pairs of oppositely disposed chambers located between said tubular passages and having communication with said second named openings, said strip being provided with openings to afford communication between the chambers of each pair.

100

105 In testimony whereof we affix our signatures in presence of two witnesses.
